CLAIM

The ornamental design for a garbage pail, as shown and described.

DESCRIPTION

FIG. 1 is a front elevational view of a garbage pail showing my new design, the rear elevational view being a mirror image of that shown;

FIG. 2 is a left side elevational view thereof;

FIG. 3 is a top plan view thereof;

FIG. 4 is a bottom plan view thereof;
FIG. 5 is a top plan view thereof in an open position; and

FIG. 6 is a front elevational view of FIG. 5.

FIG. 1.

FIG. 2.

FIG. 3.

FIG. 4.

FIG. 5.

FIG. 6.
